BOTTLE-CAP REMOVER

Emery P. Tiffault, Ballston Spa, N. Y.

Application March 6, 1937, Serial No. 129,503

2 Claims. (Cl. 65—46)

This invention relates to a device for removing container closures, and may be used advantageously for removing crown type of caps from bottles.

An object of the invention is the provision of a device whereby container closures may be conveniently removed by simple manipulations of the container, and whereby at the same time the removed closure is delivered into a suitable receptacle, thereby doing away with the trouble and annoyance of having numerous closures all over the floor behind a counter and serving bar.

A further object of the invention is the provision of a device of the indicated character which will grasp and hold the container or bottle placed in it until the closure cap thereof is completely removed, thereby eliminating dropping of the container while removing the closure cap.

A further object of the invention is the provision of a simple device well suited for economic manufacture in large quantities, and one which is of efficient and substantial design.

The invention will be fully and comprehensively understood from a consideration of the following detailed description when read in connection with the accompanying drawing which forms part of the application.

In the drawing:

Fig. 1 is a perspective view of a device embodying the features of the invention.

Fig. 2 is a front view of the device applied for use.

Fig. 3 is an enlarged section taken on the line 3—3 of Fig. 2, and illustrating the manner in which a bottle is disposed for the removal of its closure cap.

Fig. 4 is a section taken on the line 4—4 of Fig. 2.

Referring now more particularly to the drawing, it will be apparent that the device includes a metal plate 10 of any suitable shape or design in outline. The plate 10 has holes therein to accommodate suitable fastening elements such as the screws 11 whereby the device and therefore the plate may be fixed to a counter, bar, or other suitable support. The plate 10 constitutes a fixed jaw. The upper end of the plate has formed integral therewith spaced apertured lugs 12 which support a pivot 13 held against axial movement by a head 14 on one end of the pivot and a split pin or the like 15 extending thru the other end of the pivot. A rigid elongated member 16 has its upper end wrapped around the pivot 13 to effect a pivotal connection of the member 16 with respect to the plate 10, so that

said member may be moved toward and away from said plate 10. The lower end 17 of the member 16 is bent outwardly at an angle to provide a manipulating means. The member 16 thus mounted constitutes a movable jaw. The 5 plate 10 has a projection or lip 18 integral therewith, and the member 16 has a projection or lip 19 integral therewith on the inside. The projections 18 and 19 are disposed so as to engage a container closure such as a crown type of bottle cap, at points diametrically opposite each other, when the container is brought upwardly between the plate 10 and the pivoted member 16.

In accordance with another feature of the invention the movable jaw 16 has secured thereto 15 on the inside thereof a stop 20. This stop is of L-shaped formation in the present instance and is secured by means of pins 21. This stop 20 prevents the upward movement of the closure cap as it is being removed from the container. 20

The movable jaw 16 is under the influence of resilient means in the form of a coil spring 22 having one end connected with one of the pins 21, as at 23, and its opposite end is connected with one of the screws 11 as at 24. The spring 22 has a normal tendency to constantly urge the movable jaw 16 toward the fixed jaw provided by the plate 10. The movement of the jaw 16 toward the jaw 10 is limited by a bumper 25 of any suitable form carried by the upper pin 21. This pin 30 25 may be threaded so that the bumper 25 may be screwed thereon as shown in Fig. 3. By providing the bumper with a rubber head 26, it will eliminate noise when the jaw 16 moves toward the jaw 10. 35

In accordance with another feature of the invention there is provided guiding means consisting of a pair of angle members 27 rigidly secured to the plate 10. The lower ends of the members 27 converge upwardly as shown most clearly in 40 Fig. 2. The members 27 constitute means for guiding the closure end of a container or bottle for the engagement of the projections 18 and 19 with the closure or cap. With the container disposed in the manner stated and its cap engaged 45 by the projections 18 and 19, by canting the container rearwardly, the closure cap will be instantly removed.

Directly above the projection 18, there is an opening 28 in the plate 10 which is in registration 50 with a chute 29 secured to the plate 10 at the rear thereof by any suitable means as indicated at 30. The chute 29 constitutes means for receiving the removed closures or caps and for delivering them into a suitable receptacle, not 55

shown, provided for that purpose, as the closures or caps are removed. Attention is called to the fact that in the closure or cap removal operation, the latter as stated is prevented from moving upwardly by the stop 20, and the movable jaw 16 under the influence of the spring 22 causes the removed closure or cap to enter the chute 28 thru the opening 28 for disposal.

It is to be understood that this improvement is capable of extended application and is not confined to the exact showing of the drawing nor to the precise construction described, and, therefore, such changes and modifications may be made therein as to not affect the spirit of the invention nor exceed the scope thereof as expressed in the appended claims.

What is claimed as new and useful is:

1. A device for removing container closures comprising a fixed jaw and a spring pressed relatively movable jaw pivotally connected thereto, each of said jaws having projecting closure en-

gaging portions disposed for engagement with a closure for facilitating removal of a closure from a container upon which it is carried by canting the latter toward or away from the fixed jaw, and said fixed jaw having means for receiving 5 the removed closure and for delivering it into a suitable receptacle.

2. A bottle cap remover comprising a fixedly supported plate, a downwardly dependent member pivotally connected near its upper end to 10 said plate, and movable toward and away from said plate, a stop carried on said pivoted member facing toward said plate, said plate and pivoted member each carrying projecting cap 15 engaging portions disposed for cooperation with said stop to facilitate removal of a cap from the bottle to which it is applied when the bottle is canted either in a direction toward or in a direction away from the plate.
